INSULATED TILE UNIT AND STRUCTURE

Edward R. Powell, Alexandria, Ind.

Application November 25, 1935, Serial No. 51,393

12 Claims. (Cl. 72—37)

This invention relates to insulated masonry or, in other words, masonry which transmits relatively little heat in certain directions. It relates particularly to walls, roofs, ceiling and floor slabs which are mechanically strong and which resist the transfer of heat thru them between inner and outer surfaces.

A chief feature of the invention is to provide a structure for residence building or other purposes which involves the use of ceramic tile or other strong and inexpensive material involving conventional processes in its manufacture, and insert therein insulating material which insulates in the finished structure as before set forth and performs other important functions in the erection of same.

One object of the invention is to manufacture and assemble composite units which include hard structural sheets and frames enclosing relatively soft filling material, the filling material being firm enough, however, to hold and act as a form for grout or mortar used in the assembly.

Another object of the invention is to employ in certain relationships structural material such as ceramic tile or asbestos wood in combination with such insulating material as mineral wool bats or various insulating fillers or felts so that the structural material will not transmit heat around the insulating material excessively and yet will make a satisfactory structure.

Another object of the invention is to provide such composite building units and so assemble or lay them that a wall or slab is formed in one laying operation which is satisfactory in weather resistance, appearance and durability. As added advantages of the preferred forms of the invention, structures are fabricated which resist rot, fire, vermin, cracking and in general require little maintenance.

The full nature of the invention will be understood readily by referring to the accompanying drawing, the following description and claims.

In the drawing, Fig. 1 is a horizontal section of a wall embodying one form of the invention. Fig. 2 is an elevation of part of the wall of Fig. 1.

Fig. 3 is a vertical section taken in plane 3—3 of Fig. 2 and in the direction of the arrows.

Fig. 4 is a horizontal section of a wall of modified form.

Fig. 5 is a vertical section of a slab which embodies the invention and is suitable for use as a ceiling, floor or roof.

Fig. 6 is a vertical section taken in plane 6—6 of Fig. 5 in either direction.

Referring to Fig. 1, 11 indicates a hollow tile of conventional material and processing having relatively thin through webs 14 at the ends only. Comparatively large flat sheets of material are exposed on opposite sides of the wall and the intervening space is filled with insulating material 10. Satisfactory materials for the purpose are fired shale or clay tile and mineral wool bats of relatively firm composition and water-repellent character. The tile are laid up employing conventional tools and relatively hard mortar 12. A strip of resilient material 13 is laid in the joint and has the effect of interrupting the mortar joint. This material is preferably oiled with an excess of wax or oil-bearing liquid or other water-repellent liquid so that it moistens the adjacent webs 14 of the tile at 11a and thus prevents them from transmitting water by capillary or wick action thru the wall. In this way the wall is well waterproofed since water will not absorb from the tile to the insulating filling under normal conditions. The horizontal mortar joints are reinforced with metal rods 29, see Fig. 3.

If preferred, the through webs 14 of the tile 11 before laying may be treated at 11a with wax 25 solution or equivalent material to prevent water conduction.

Typical mortar for use in this erection consists of one part Portland cement to four of sand and some plasticizing material such as hydrated lime 30 in lesser proportion, with enough water to make a mortar of desired consistency. Certain ground clays have been used satisfactorily for plasticizing. Other compositions may be desirable under special conditions.

For vertical reinforcement, a channel is formed in the yielding insulation adjacent the webs of the tile and grout 15 is poured into the space thus formed. Vertical rods 16 are inserted into 40 this space or into the grout while still soft.

A wall thus built although employing inexpensive materials has unusual merit. It may be lifted in sections of considerable size by eyes or hooks attached to or formed in the ends of rods 45 16. It will permit assembling horizontally and standing up without fracture. It permits streams of water to run down one side for long periods of time without damage or wetting the other side. It may be assembled in a shop in panels 50 and shipped to the building site. In general, it involves about the minimum of material for a wall of great strength and durability since each material in it performs a valuable and dependent function. It is preferably built of durable fire- 55

proof materials and, if properly built, is highly resistant to all common forms of destruction.

The insulating material 10 should be highly water-repellent and readily formable into chan-

nels for the grout. With certain grades of treated mineral wool bats, it has been demon-

strated that moisture will not absorb from the tile to the bat. Usually 1½ to 8 per cent of wax, resin, grease or combinations thereof added

10 evenly to clay or mineral wool have the effect of rendering same relatively non-absorbent or water-repellent. Clay tile is commonly of finer

porosity than the insulating material which cir-

15 cumstance aids in arresting the capillary travel of moisture through the wall. Other insulating

fills may also be used such as treated expanded clay, treated cork and jute and cotton felts if stiffened slightly.

If the insulation or fill in the wall will not re-

20 tain its shape, a channel of sheet material 24 may be used to confine the grout 15. Such loose

fills may be poured into each tile after setting. Mineral wool bats are preferably inserted before

laying the tile.

25 Expanded clay for a fill of this type may be made by the process described in my application

Method of forming expanded clay masses, Serial No. 667,048 filed Dec. 7, 1933. The clay is ex-

30 panded after mixing with oil and is dried but may be left unfired so that the oil acts as a

binder and waterproofing.

In the assembled unit shown in Fig. 4, the tile is formed of two channels 17 and 26 secured with

dowels 21. A layer of resilient material 28 such

35 as saturated roofing felt is used between flanges 19 and 22. A strip of felt 13 is used as in Fig. 1 to interrupt the mortar joint but the felt needs

no excess of oil in this construction. The ad-

40 vantages of this structure over that illustrated in Figs. 1 to 3, inclusive, are that the interrup-

tion of heat conduction is more complete. The

channels 17 and 26 may be rolled after extruding

in the manufacture to secure more variety of

45 texture than is possible with hollow tile. The

main structural wall is residual in the heavy-

50 web channels 17, and channels 26 may form

merely a sort of suspended closure for the spaces

if such an arrangement is desired.

The consistency of the interrupting material

55 strip 13 in each instance is preferably adjusted

so that it will be stiff enough to separate the

mortar joint into two parts as shown. It should

be yielding enough, however, to compress under

the force of laying the tile so that a seal will be

55 formed between adjacent units in spite of slight

cracking of the structure. The strip 13 should

be under some compression in the finished struc-

60 ture. It may be laid on the tile before or after

spreading the mortar. In a joint thus con-

65 structed the mortar alone is not depended on

for a seal but is primarily depended upon for

a bond.

The water-repellent nature of the insulation

permits mortar to be spread in contact there-

65 with. The insulation will not absorb water ap-

preciablely from the wet mortar. This would be

undesirable since the water is needed in the

mortar to complete the setting of the cement

and is undesirable in the insulation.

70 The slab of Figs. 5 and 6 is adapted to resist

bending and may be used to span the usual width

of residence rooms for floors and roofs. The top

or compression member 23 is of heavy walled

75 tile made in conventional manner. The lighter

tile 26 is suspended from flange 25 of tile 23 by

ties 30. These may be metal, tile material or asbestos wood. Insulating material 10 is used as in the walls. The tile 23 are preferably made smaller than tile 26 so that there is room for a substantial reinforced joint or beam 31 enclosing reinforcing rod 29. The joints thus formed act as beams or joists to carry the slab. The insulating material, if not self-sustaining on the edges, may be contained in cardboard forms 32. For nearly complete thermal separation of the 10

upper and lower tile, felt pads or equivalent material 20 should be used. Strips of hair felt or mineral wool felt are satisfactory for these pur-

poses. Tile 26 may be perforated to admit sound and thus form an acoustical treatment in com- 15

bination with the insulation 10, which may be selected for sound absorbing as well as thermal properties. Members 24 may be pins, dowels or

bolts according to the nature of the ties 30 which are to be secured to the flanges or webs. 20

The upper tile are preferably coated with a thin layer of mortar or concrete 27 for leveling up. This is in turn treated or coated with ma-

terial 28 for flooring or roofing service. In this way a complete closure for the top of a building 25

may be formed. False work is needed to support the slab as shown until the assembly is complete and the mortar has set. If desired, light metal

beams 18 (shown dotted) may be used running one way to carry the units for erection purposes. 30

Assembled beams of the type known as "junior beams" are satisfactory for this service. The tile may be hung from them by means of short rods. These beams may be strong enough only for the

dead load of the floor and may be assisted by 35

central support. Additional strength is secured by the concrete for carrying the service loads.

The waterproof feature of the methods and

structure may be used independently of the in-

40 sulation and reinforcement in vertical walls. In-

sulation is not always required within the tile nor reinforcement in the wall. Load bearing

horizontal slabs are not practical without re-

inforcement, but reinforcement is optional in ver-

45 tical walls. Closures of some sort are necessary in lieu of filling for tile of the type described if reinforcement is to be used. In general, the pre-

ferred form of the invention involves insulation,

waterproofing and reinforcement and all three

50 features are used for the best results with the least materials but any one of the three features may be used separately for minor modification.

Furthermore, a great many details of build-

ing construction are fully contemplated within

the scope of this invention but are too numerous

55 to illustrate and describe. These details include

tying walls to footings, joining floors and roofs to

walls, tying in corners and partitions, mounting

50 window sashes and door jambs, inserting pipes

and conductors and mounting fixtures. These

60 features and many others are generally obtained

by a variety size or shape in the tile and com-

binations in which they are assembled, and the

cutting or drilling thereof when necessary. The

65 general method of construction which is herein

disclosed may be carried out throughout the

building. A few odd places may be filled in with

brick of the same finish as the tile backed up

with insulation. It is well known that ingenuity

is needed in the erection of any building which

70 is not fully prefabricated or standardized.

Using such ingenuity does not constitute a de-

parture from the spirit of this invention nor

75 essential addition thereto, reference being had

to the appended claims.

The invention claimed is:

1. A hollow tile building unit as an article of manufacture, including hard structural inner and outer shells with relative little web material connecting same, water repellent insulating material substantially filling the enclosed space between the shells, and means on the through webs to prevent capillary conduction of water therethrough.
- 10 2. A unit as defined by claim 1, characterized by the insulating material including a channel formation and by the addition of grout therein for the purpose set forth.
- 15 3. A hollow tile building unit as an article of manufacture, including hard structural inner and outer sheets with relatively little web material connecting same, the web material consisting of independent flanges formed integral with the sheets, means mechanically holding the flanges in spaced relation, and water repellent means interposed in the first mentioned means for separating the flanges substantially as described.
- 20 4. A unit as defined by claim 3, characterized by the addition of a preassembled water repellent insulation substantially filling the space between the sheets.
- 25 5. A unit adapted for assembling into horizontal load bearing slabs, including a heavy compression resisting tile, a closure tile lighter than the compression tile, means suspended from the first mentioned, for suspending the closure tile, and water repellent insulating material substantially filling the space between these tiles and adapted to prevent grout entrance to the space between these tiles at the joints.
- 30 6. A structure, including hollow tile units assembled as a single wall, mortar bond joints therebetween and of interrupted character, and an interrupting resilient material strip under slight compression and intermediate the inner and outer surfaces of the structure and in all
- 35 joints for maintaining an interrupting seal in spite of slight cracking at any joint.
- 40 7. A structure as defined by claim 6, characterized by the addition of insulating material substantially filling the hollow portions of the tile units.
- 45 8. A structure including hollow tile units assembled as a single wall, water repellent insulating material substantially filling the hollow portions of the units, mortar bond joints of interrupted character connecting said units, strips of resilient material in all mortar joints intermediate the inner and outer surfaces of the structure, and means upon the through webs of the tile to prevent capillary transmission of water through the single layer structure.
- 50 9. A structure as defined by claim 8, characterized by the addition of reenforcing rods imbedded in certain mortar joints.
- 55 10. As an article of manufacture, a composite building unit including two channel shaped tile units, the flanges of the channels being turned together, means mechanically holding the flanges together in spaced relation but not intimately contacting, and water repellent, insulating material substantially filling the space enclosed by the two channels.
- 60 11. A horizontal building slab which includes composite units consisting of load bearing tile, decorative tile of greater horizontal dimensions, means suspending the latter from the former, other means thermally insulating the tiles, the units being arranged in horizontal series to form beam shaped spaces, and reenforced concrete in these spaces, the reenforcement of said concrete being near the lower extremities of the beam.
- 65 12. As an article of manufacture, a hollow tile of generally hollow rectangular solid shape, the tile being of fired ceramic material, and treated, water repellent, expanded clay substantially filling the hollow portion of the tile.

EDWARD R. POWELL.
